UNITED STATES PATENT OFFICE.

LOUIS H. BERRY, OF MINNEAPOLIS, MINNESOTA.

CHARGING-BUCKET.

1,333,152.

Specification of Letters Patent.

Patented Mar. 9, 1920.

Application filed June 20, 1918. Serial No. 241,068.

To all whom it may concern:

Be it known that I, LOUIS H. BERRY, a citizen of the United States, and a resident of Minneapolis, in the county of Hennepin and State of Minnesota, have invented certain new and useful Improvements in a Charging-Bucket, of which the following is a specification.

This invention relates to a bucket to be used in charging steel furnaces and the like.

One object of my invention is to provide in a charging bucket an improved form of releasable trap door.

15 Another object of my invention is to provide a split bucket and means for locking the same in its closed position.

Another object of my invention is to provide improved means of supporting the trap door when closed.

With these and incidental objects in view, the invention consists of certain novel features of construction and combination of parts, the essential elements of which are 25 hereinafter described with reference to the drawings which accompany and form a part of this specification.

In the drawing Figure 1 is a side elevation of my improved charging bucket, Fig. 30 2 is a plan view of the same, Fig. 3 is a side elevation of my improved bucket when opened, Fig. 4 is an enlarged detail of the means used for locking the operating lever, Fig. 5 is an enlarged view of the cam used to 35 close the two halves of the bucket together, and Fig. 6 is a section taken on the line 6—6 Fig. 3.

As shown in Fig. 1 my improved charging bucket consists primarily of a split cylindrical shell comprising the half members 40 1 and 2 Fig. 1.

Each half is suitably reinforced by bands of iron 2, 3 and 4 for the half 1 and 5, 6 and 7 for the half 2.

45 Carried by the reinforcements of the halves is a pair of hinges 8 thus allowing the bucket to split along the line 9.

Hinged at 10 to the half 1 the cam member 11 engages with the pin 12 rigidly carried by the half 2, a similar construction being used on the opposite side not shown.

The hinge 10 carried in the half 1 is supported at its outer end by the yoke 13 and the pin 12 similarly supported by the yoke 14.

55 Riveted or otherwise suitably attached to

the cam member 11 is a bail shaped lever 15 connecting the similar cam shaped members on each side of the bucket and a central socket 16 is carried on this bail for the connection thereto of a pipe or handle for the more simple manipulation of the bail.

60 It is self-evident that the swinging down of the bail 15 forces the two halves of the bucket apart by the cam action of the cam member 11 on the pin 12.

Especial arrangement is provided for locking the bail 15 in its upper position as shown in an enlarged detail in Fig. 4.

An angle plate 17 riveted to the half 2 70 carries by sliding engagement a catch 18 on which the socket 16 rests.

Hinged to the socket at 19 is a trigger 20 adapted to be swung into engagement with the lip 21 of the catch 18 to draw the 75 catch from engagement with the socket 16, thereby releasing the bail 15 and opening the bucket. An aperture or lip 22 is provided for attaching thereto a chain to allow the easy operation of the trigger.

80 As shown in Fig. 2 the trap door is composed of four segments 23, 24, 25 and 26 hinged at 27, 28, 29 and 30 respectively to the bucket, the hinges 29 and 30 are offset, as shown in Fig. 1.

85 The segments 25 and 26 each have lips 31, Figs. 2 and 6, adapted to rest on and be supported by the segments 23 and 24 when the bucket is closed. The segments 23 and 24 are provided at their inner ends with engaging members comprising the male member 32 and the female member 33, Fig. 3.

90 When the bucket is opened as shown in Fig. 3 and is to be closed, the segments 25 and 26 are first swung upwardly, the segments 23 and 24 then swung upwardly and the male and female members 32 and 33 engaged, and the bail 15 then swung upwardly and latched, the upward movement of the bail closing the two halves 1 and 2 of the 100 bucket together and thus positively locking the members 32 and 33 together.

95 As it is impossible for the male and female members to become disengaged without the bucket splitting, and as the segments 105 25 and 26 are securely held by their lips 31 above the segments 23 and 24, it will be seen that the trap door cannot be released without the splitting movement of the bucket which in turn depends upon the position 110 of the bail 15.

Four lugs 34 are provided to prevent the

segmental door members from swinging beyond the horizontal position. This is important in a furnace charging bucket as the doors would seriously injure the lining of the furnace if they swung beyond the horizontal when they were dropped inside of the hearth.

It will be noted in Figs. 1 and 3 that these four lugs together with the lip 35, Figs. 1 10 and 3, provide five points for support for the bucket when it is resting on the foundry floor to be charged and the center support 35 is important as it prevents possible breakage of the doors when the charge is being dropped into the bucket.

While I have described my invention and illustrated it in one particular design, I do not wish it understood that I limit myself to this construction, as it is evident that the 20 invention may be varied in many ways within the scope of the following claims.

I claim—

1. In a charging bucket the combination 25 with a bucket body split longitudinally and hinged at its upper end, of a trap door carried on the lower end of said body, means for locking said trap door in a closed position said locking means being disengaged by the opening of the slit of said body.

2. In a charging bucket the combination 35 of a bucket body split longitudinally and having the halves thereof hinged together at their upper ends, a pair of segmental doors hinged to the lower end of said body, means carried on said doors for locking said doors closed when said split body is closed, said locking means being out of engagement when said split body is opened.

3. In a charging bucket the combination 40 of a bucket body split longitudinally and having the halves thereof hinged together at their upper ends, a pair of segmental doors hinged to the lower end of said body, means carried on said doors for locking said doors closed when said split body is closed,

said locking means being out of engagement when said split body is opened and means carried by one of the halves of said split body for opening or closing the split in said body.

4. In a charging bucket the combination 55 of a bucket body split longitudinally and hinged at its upper end, a trap door, means carried by one half of said split body co-operating with means carried on the other half of said split body for opening and closing the split in said body, said trap door having means for holding it in a closed position when said split is closed and being 60 released when said split is open.

5. In a charging bucket the combination 65 of a bucket body split longitudinally and hinged at its upper end, a trap door, means carried by one half of said split body co-operating with means carried on the other half of said split body for opening and closing the split in said body, a latch for holding said means in position when said split is closed, and means for disengaging said latch to allow the opening of the split in said body, 70 the opening of the split in said body releasing said trap door.

6. In a charging bucket the combination 75 with a split body hinged together at one end of a segmental trap door comprising four segments hinged to said body, interlocking means carried on two of said segments for maintaining said segments closed when said means are engaged, and means 80 carried by the remainder of said segments for supporting weight carried thereby on said interlocking segmental members.

7. In a charging bucket the combination 85 with a bucket body split longitudinally and hinged at its upper end of a trap door carried on the lower end of said body for locking said trap door when the split of said body is closed, said means being unlocked by the opening of the split of said 90 body.

LOUIS H. BERRY.
